United States Patent Office

Des. 221,324
Patented July 27, 1971

221,324

HANDLEBAR

Carlton P. Pawsat and Robert F. Humlong, Maysville, Ky., assignors to Wald Manufacturing Company, Inc., Maysville, Ky.

Filed June 29, 1970, Ser. No. 23,733

Term of patent 14 years

Int. Cl. D12—14

U.S. Cl. D90—11

FIG. 1 is a front elevation view of a handlebar showing our new design.

FIG. 2 is a side elevation view thereof as seen from the right side of FIG. 1.

The characteristic features of our design reside in the configuration and appearance of the reflective surfaces on the risers and horizontal portions of the handlebar.

We claim:

The ornamental design for a handlebar, as shown and described.
